UNITED STATES PATENT OFFICE.

HENRY J. BADDELEY, OF NAPA, CALIFORNIA.

TALLY-BOARD.

SPECIFICATION forming part of Letters Patent No. 243,058, dated June 21, 1881.

Application filed September 23, 1880. (No model.)

To all whom it may concern:

Be it known that I, HENRY J. BADDELEY, of Napa, in the county of Napa and State of California, have invented a new and useful 5 Tallying-Machine, of which the following is a specification.

My invention relates to that class of machines or apparatus in which notches or scores are cut for tallying games, ballots, &c.; and 10 the object of my invention is to provide a means whereby the number of votes or games can be readily and correctly ascertained as the same are called off. I accomplish this object by the machine or apparatus illustrated in the 15 accompanying drawings, in which—

Figure 1 is a front view of my machine or apparatus with lower portion broken away. Fig. 2 is a longitudinal section of operating-key and toothed rack. Fig. 3 is an enlarged 20 view of rack, showing the holes between the teeth thereof. Fig. 4 is a bottom view of rack, guides, spring, and toothed tallying-wheel. Fig. 5 is a cross-section of ways and sliding rack.

I construct my tallying-board of any suitable material, and at intervals of space are cut the slots A A, having the necessary scores B B cut along the faces thereof. Back of these slots I connect ways C, in which the toothed rack 30 D operates, it being held in place by the cross-plates E. A pin or indicating-wheel, F, is also placed at the rear end of each slot, and is operated by the flat spring-arm G as the toothed rack approaches the end of the slot. The head 35 of the slot is provided with an enlarged opening, to one side of which is hinged the key-carrying box H, which, when closed, shuts down upon the toothed rack. This box contains the operating-key a, provided with a 40 point, b, which enters the holes b' of the rack, to hold and keep it in position as each tallying is made. Each of the keys is also provided with a pawl, c, and spring d, the end of the pawl engaging in the teeth of the rack, and the 45 spring presses it down as the rack is advanced notch by notch.

To the end of the pin on which the key is pivoted is attached a hammer, e, which strikes the gong f as each movement of the key is 50 made, and the rack advances forward one tooth. Each rack is provided near its forward end

with an index-finger, g, that projects through the slot A and indicates the position of the rack with relation to the score B.

In practice the name of a candidate or player 55 is attached to or near the head of each slot on the face of the board or frame, and as the teller calls out the name the operator presses the key, which moves the toothed rack one point or tooth forward, which is indicated by the score 60 on the plate and indicating-point at the end of the toothed rack.

The drawings do not represent the scale B as it is in the working-machine, only a portion 65 of the dividing-lines of the scale being shown, in order that crowding of the lines may be avoided. My intention is to have a scale numbered from 0 to 100, inclusive.

To place the machine in position to commence operations, each rack is drawn outward until 70 the index-finger g stands at 0 and the indicating-wheel F is turned so that the 0 on its face is visible through the opening made in the tally-board for that purpose. The face of this wheel is provided with figures or numerals, 75 from 1 to 10, inclusive. Upon the first score or count being made known the operator causes the index-finger on the rack to be moved one notch forward. It will then stand opposite the figure 1 upon the scale. This is repeated until 80 the number 100 has been reached, when the spring-arm G will simultaneously engage with a tooth upon the pin or indicating-wheel F and move it one point, thus displaying the figure 1 through the opening in the tally-board, and 85 so on until the number 10 upon the wheel has been reached and shown, which would indicate that ten times one hundred had been counted. The numbers remaining over before or after any hundred has been counted are indicated on the 90 scale B by the position of the index-finger g.

At every movement of the key the hammer will strike one against the gong or bell, which gives additional warning that a movement has been made of the toothed rack opposite the name 95 which has been called by the teller. When the end of the score is reached the key-box is folded back and the rack drawn out until the indicating-finger g at the end of the rack stands opposite the first notch of the score, when the 100 action and movements are again repeated.

By this means it is believed that a less num-

ber of tallying-clerks will be required at elections on counting the ballots and a much more rapid and accurate count will be had than by any other means yet discovered.

5 Having thus described my invention, what I claim, and desire to secure by Letters Patent, is—

1. The combination, with a slotted tallying-board provided with scores or tally-marks and 10 a gong, of a movable toothed rack provided with an index-finger, an operating-key contained in a hinged box, and having a hammer attached to the pin on which it is pivoted, and an indicating-wheel operated by a flat spring-15 arm, substantially as shown and described.

2. The combination, with a tallying-board

having slots A and scores B, of the toothed racks D, moving in ways C C, connected by cross-plates E E, and provided with spring-arms G, the hinged box H, containing an operating-key, a, provided with tooth b, pawl c, and spring d, and the indicating-wheel F, provided with numerals, all constructed and arranged substantially as and for the purpose specified. 20

In testimony that I claim the foregoing I 25 have hereunto set my hand and seal this 24th day of August, 1880.

HENRY J. BADDELEY. [L. S.]
